UNITED STATES PATENT OFFICE.

HENRY C. EGERTON, OF PASSAIC, NEW JERSEY, ASSIGNOR TO WESTERN ELECTRIC COMPANY, INCORPORATED, OF NEW YORK, N. Y., A CORPORATION OF NEW YORK.

TELEPHONE-AMPLIFIER.

1,337,694.

Specification of Letters Patent. Patented Apr. 20, 1920.

Application filed June 7, 1916. Serial No. 102,205.

To all whom it may concern:

Be it known that I, HENRY C. EGERTON, a citizen of the United States, residing at Passaic, in the county of Passaic and State of New Jersey, have invented certain new and useful Improvements in Telephone Amplifiers, of which the following is a full, clear, concise, and exact description.

This invention relates to telephone instruments, and more particularly to improvements in devices for relaying telephonic currents, or for reproducing such currents aurally, all in a manner to respectively secure amplifications thereof and articulate 15 sounds of relatively considerable volume.

The principal object of this invention is to simplify and to improve the working efficiency of telephone devices of this character.

In accordance with this invention, in substitution of working bearings, the armature of an electromagnetic structure is fixed to work against torsional flexing stresses thereby set up in a rigidly supported member, all 20 in response to telephonic currents suitably applied to the device. Such motor telephone currents may be either relayed or reproduced aurally by utilizing the resulting movements or vibrations of the armature to 25 respectively operate telephone transmitting or receiving diaphragms.

This invention is illustrated in the accompanying drawings, in which Figure 1 is a side sectional view of the instrument arranged in a manner to operate one transmitter button.

Fig. 2 is a side view partially in section corresponding with the next right-hand face of the assembly shown in Fig. 1.

Fig. 3 is a perspective, with the outer casing removed, of the assembly shown in Figs. 1 and 2.

Figs. 4 and 5 are respectively the same as Figs. 1 and 2, except that the structure is modified to operate two transmitter buttons.

Fig. 6 is a combined sectional and diagrammatic side view of the electromagnetic structure with operating circuits and also illustrating a method of applying this device to operate a diaphragm to thereby convert telephone currents into articulate sounds.

In describing this invention in connection with the drawings, similar characters of ref-

erence will be used to indicate corresponding parts in all the figures.

In the present embodiment of this invention, the instrument comprises a supporting base 5, an outer protective casing 6 and an inner framework 7, all constructed, preferably, of suitable non-magnetizable metal. An E-shaped magnet frame 9 carries on its pole members 10 and 12 sensitizing or polarizing windings 13 and 14, respectively, and also windings 15 and 16, respectively, for telephonic currents. An armature 20 is fixed, intermediate its ends, to the inner edge of a U-shaped member 21, the ends of which are reinforced by means of details 22. Slots 23, formed in the frame 7, are adapted to receive the reinforced ends of the armature support 21, and when these are entered therein to a depth for securing a predetermined air-gap adjustment between the face of the armature 20 and the pole members 10, 15 and 12 of the magnet frame 9, these ends may be firmly clamped at such point by means of set screws 24.

In operating this device, a source of unidirectional current 8 applied, as shown, to the windings 13 and 14, thereby produces magnetism of uniform sign in the outer pole members 10 and 12, each of which then acts accumulatively with the oppositely magnetized central pole member 11. The relation of the windings 15 and 16, one with the other, is such that when telephonic currents are applied thereto, as from an induction coil 17, worked by a distant transmitter 18 over the circuit shown, magnetism of respectively opposite polarity will be accordingly set up in the pole members 10 and 12, thereby causing such magnetic stresses to move the ends of the polarized armature 20 in opposite directions. The movements of 95 the armature 20 correspond in direction and amplitude with the direction and strength of the applied telephonic currents. Therefore, a diaphragm 25 suitably supported at its periphery when attached to the armature 100 20, as by means of a member 26, will execute movements to transform such mechanical vibrations of the armature into articulate sounds.

In relaying telephonic currents, it has 105 been found that a granular carbon transmitter unit, such as shown in detail section in Fig. 1, gives the best results. This trans-

mitter unit comprises a mounting block 30, preferably of brass, suitably secured to the base 5. Block 30 has a cylindrical cup-shaped portion into which is tightly fitted a brass sleeve 31, having a portion 32 with large internal diameter and a portion 33 of smaller internal diameter. A paper insulating sleeve 34 covers the inner surface of portion 32, while a coating 35 of electrically insulating but comparatively high heat conducting japan or enamel covers the inner surface of portion 33 overrunning both edges as shown. A back electrode 36, preferably a carbon disk, is fitted into the portion 34 of sleeve 31 but is insulated therefrom by the paper sleeve 34, the japan and a mica washer 37. A front electrode 38, also in the form of a carbon disk is carried by and in electrical engagement with armature 20 and is separated from sleeve 31 by a washer 39 preferably of felt. The chamber 40 thus formed by the inner japanned walls of portion 33 of sleeve 31 and the front and back electrode 38 and 36 contains the usual 25 comminuted material such as granulated carbon. This form of unit provides good insulation between the parts while, at the same time, the heat produced by the passage of current through the comminuted material 30 is readily dissipated. The back electrode 36 is held in place by a spring 41, which, engaging an insulated stud 42 to which is connected a suitable conductor 43, also forms a part of the electrical circuit of the transmitter.

As shown in Figs. 4 and 5 of the drawing, the armature of this electromagnetic system may be conveniently adapted to operate a plurality of transmitter buttons, as 40 45 and 46, each of which may correspond with the transmitter button already described.

A plurality of terminals 47 suitably bushed and insulated from the base 5 on which they are, for convenience, mounted, serve as terminals for the various circuits of this device and as junction points to which exterior conductors may be connected.

What is claimed is:

50 1. An electromagnetic structure comprising a core having a plurality of laterally spaced pole pieces, polarizing means for said core, a winding for actuating current associated with said core, supporting means, a resilient armature carrying member associated with said supporting means, and an armature fixed to said member positioned entirely to one side of said core overlying said pole pieces and normally maintained 55 in a definite air gap relation to said pole pieces by said member; said armature being movable in response to actuating currents in said winding to vary such air gap relation against the torsion of said member.

55 2. An electromagnetic structure comprising

ing a core having a plurality of laterally spaced pole pieces, polarizing means for said core, a winding for actuating current associated with said core, supporting means, a resilient armature carrying member fixed 70 to said supporting means intermediate said pole pieces, and an armature fixed to said member positioned entirely to one side of said core overlying said pole pieces and normally maintained in a definite air gap relation to said pole pieces by said member; said armature being movable in response to actuating currents in said winding to vary such air gap relation against the torsion of said member. 80

3. An amplifier comprising a core having a plurality of laterally spaced pole pieces, polarizing means for said core, a winding for actuating current associated with said core, supporting means, a resilient armature carrying member fixed to said supporting means, an armature fixed to said member positioned entirely to one side of said core overlying said pole pieces and normally maintained in a definite air gap relation to 90 said pole pieces by said member, and a variable resistance element operatively associated with said armature and arranged on the side of said armature opposite to that presented to said pole pieces; said armature being movable in response to actuating currents in said winding to vary such air gap relation against the torsion of said member and to correspondingly operate said resistance element. 95

4. A telephone amplifier comprising a core having a plurality of laterally spaced pole pieces, polarizing means for said core, a winding for telephonic currents associated with said core, supporting means, a resilient armature carrying member carried by said supporting means, an armature fixed intermediate of its length to said member and overlying said pole pieces, and a pair of separate telephone transmitter elements, 110 one being operatively connected to one end of said armature and the other operatively connected to the other end of said armature to provide simultaneous operation of both elements on movement of said armature. 115

5. A telephone amplifier comprising a core having a plurality of laterally spaced pole pieces, polarizing means for said core, a winding for actuating current associated with said core, supporting means, a resilient armature carrying member fixed to said supporting means, an armature fixed intermediate of its length to said member overlying and extending beyond said pole pieces, and a pair of separate transmitter elements, 125 one being operatively connected to one end of said armature beyond one of the pole pieces and the other being operatively connected to the other end of the armature beyond another of the pole pieces to provide 130

simultaneous operation of both elements on movement of said armature.

6. A telephone amplifier comprising a core having a plurality of spaced pole pieces, polarizing means for said core, a winding for telephonic currents, supporting means, a resilient armature carrying member fixed to said supporting means, an armature fixed to said carrying member and positioned at one side of said core to overlie said pole pieces, said armature being movable to torsion said member in response to telephonic currents in said winding, and a pair of variable resistance elements, one secured to one end of said armature and the other secured to the other end of said armature, and both operated by said armature.

7. A telephone amplifier comprising a core having a plurality of spaced pole pieces, polarizing means for said core, a winding for telephonic currents, supporting means, a resilient armature carrying mem-

ber fixed to said supporting means, an armature fixed to said carrying member and positioned at one side of said core to overlie said pole pieces, said armature being movable to torsion said member in response to telephonic currents in said winding, and a pair of variable resistance elements each comprising a front and a rear electrode and having their respective front electrodes secured to opposite ends of said armature for movement therewith.

8. An electromagnetic structure comprising a core having a plurality of spaced pole pieces, polarizing means for said core, supporting means, a U-shaped resilient carrying member having the legs thereof engaged by said supporting means, and an armature fixed to and transversely of the base of said member and movable to torsion said member.

In witness whereof, I hereunto subscribe my name this 3rd day of June, A. D. 1916. 45
HENRY C. EGERTON.
